PRINTER FOR MORSE CODE SIGNALS

Richard E. Mathes, Silver Spring, Md., assignor
to Radio Corporation of America, a corporation
of Delaware

Application February 22, 1945, Serial No. 579,257

7 Claims. (Cl. 178—26)

1

This invention relates to printing arrangements for Morse code telegraph signals, either in wire or radio systems.

At the present time Morse code signals are not printed directly from the signal pulses received at the station. Pulses first operate a "reperforator" mechanism to perforate a paper tape. The perforated tape is then run through the printer, the most commonly used of which is the Creed printer such as is described in the U. S. Patent 1,529,873, March 17, 1925.

To minimize the delay, the tape, as it issues from the reperforator, is run through the printing mechanism, and to prevent breaking the tape through non-synchronous operation of the two devices, a loop of slack tape must be maintained between the reperforator and the Creed printer.

The use of tape is objectionable, as it requires the close attention of the operator to prevent snarling and to make sure that neither too much nor too little tape remains in the loop. Furthermore, when signals are reperforated, there is always a delay so that the message cannot at once be utilized. While this delay is normally of the order of a minute or so, this is quite often serious in certain types of communication, for example, in stock market reports.

It is an object of this invention to avoid the use of tape and equivalents in printing Morse telegraph signals, and to operate the printer directly by the signals as they are received.

Another object of the invention is to reduce the cost of telegraph printing by elimination of the use of tape.

Another object of the invention is to control the selection of printer code bars by the signals in the last half cycle of the code characters and to control the printing mechanism by the signal in the first half cycle of the following letter or word space cycle.

Another object is to reduce the number of selector bars required, by controlling the selection in the second half of the dot cycles instead of the first.

Other objects of the invention will appear in the following description, reference being had to the drawings, in which:

Figure 1 is a plan view of my invention.

Figure 2 is a front elevation of the parts shown in Figure 1, the sectioning of a part of this figure being taken on the line 2—2 of Figure 1.

Figure 3 is an end elevation of the parts of Figure 1, certain parts being omitted.

Figure 4 is a rear elevation of a certain combination of elements of Figure 1.

2

Figures 5, 6 and 7 are detail sectional views of the selector bars, taken on the lines 5—5, 6—6, 7—7, respectively, of Figure 1.

Figure 8 is an enlarged detail view of the mechanism for operating the selector bars, certain parts being omitted.

Figure 9 is a sectional view taken on the line 9—9 of Figure 8, the selector bars being shown in dotted lines to illustrate the operation.

Figure 10 is a still further enlarged detail of the tilting table for elevating the operating bars.

Figure 11 is an enlarged detail plan of the armature extension and certain co-acting parts.

Figure 12 is a sectional elevation taken on the line 12—12 of Figure 11.

Figure 13 is an end view of the parts shown in Figure 11.

Figure 14 is a series of graphs illustrating the surfaces of the rotary cams in relation to the cam followers at the start of the printing operation.

Figure 15 is a section of a detail taken on the line 15—15 of Figure 2.

Figure 16 is a diagram illustrating the position of certain parts in respect to the dot cycle.

Figure 17 is a semi-diagrammatic illustration of one way of slotting the selector bars to receive the associated pull bars of a printer utilizing my improvement.

Figure 18 illustrates the Morse cable code, the space between adjacent lines being a half dot cycle.

Prior art printers for Morse-type signals, such as the Creed, for example, require a special selecting mechanism because of the unequal length of the various code elements. In the Morse code the shortest signal is the letter E, having one dot cycle, and the longest is zero, having five dashes, or ten dot cycles. With such variable length

characters, it has heretofore been thought impossible to use the mechanism of the well-known printers for equal length characters, such as the Baudot code, because the end of the signal is difficult to determine. I have evolved a method whereby the termination of a code signal can be sensed, irrespective of the signal length, thus making it possible to utilize Baudot types of printers as well as Creed printers and my improvement enables one to reduce the number of code bars to less than half the usual number.

The sensing of the beginning and end of the Morse code signals is based on the fact that the first half cycle of every code signal is necessarily a mark, and the first half cycle after a completed character is necessarily a space. The manner in

which my improved apparatus takes advantage of these facts will now be explained.

By way of example I have illustrated my invention in connection with the start-stop type of printing mechanism of the type shown in the patent to Morton and Krum, 1,745,633, February 4, 1930, from which its use with other types will be apparent.

Referring to Figs. 1 and 2, an electric motor (not shown) is geared to rotate the shaft 1 in the direction of the arrow shown in Fig. 1 through worm gear 2. This shaft has rigidly keyed thereto clutch member 3 and worm gear 4, so that these parts are rotated by the motor continuously. Loosely journaled on shaft 1 is a member having cams 5 and 6 with a hub 7 and a gear 8. Clutch member 9 is splined on the hub 7 so that it can be brought into and out of engagement with the cooperating clutch member 3. Spring 10 tends to force the clutch member 9 into engagement with the clutch member 3. When the two clutch members are enmeshed, cams 5 and 6 and gear 8 are rotated with the shaft 1.

Shaft 1 is journaled at 11 and 12 in a frame member 13 secured on the base (not shown). The worm gear 4 meshes with a cooperating gear 15, having twice its pitch diameter. Gear 15 is keyed to stub shaft 16, to which is keyed slip clutch member 17. This stub shaft is journaled at 18 in the frame member 13. The cooperating slip clutch member 19 is splined on another shaft 20, journaled at 21 and 22 in frame member 23, which may either be separate or integral with the frame member 13. A four-entry worm gear 24 meshes with gear 25, keyed to stub shaft 26. Shafts 20 and 26 rotate in the direction of the arrow in Fig. 1. Spring 27 on shaft 20 abuts against the worm 24 and the clutch member 19 to produce the desired pressure between the clutch members 17 and 19. A cam wheel 28 is rigidly fastened to the end of shaft 20. This cam wheel has two cam lugs 29 and 30 on opposite diametric points of its surface (Figs. 1 and 11).

A stop lever 31 is pivoted at 32 in the frame member 13 (Figs. 1 and 4) and is positioned to enter the channel 33 of the sliding clutch member 9. When this stop lever is brought into the channel 33, its end 34 engages the cam wall 35 and forces the member 9 out of engagement with the clutch member 3 against the tension of spring 10. Thereupon, the end 34 engages the abutment 36 and holds the clutch in disengaged position. Spring 37 tends to hold the stop lever 31 out of the groove 33 to permit the two clutch members 3 and 9 to engage. This stop lever is forced into groove 33 by bell crank lever 38 under action of stop lever 39 pivoted at 40 to frame member 13. Spring 41, having one end fastened to one end of the stop lever 39 and the other end fastened to the frame member 13, tends to disengage the end 42 from the stop notch in clutch member 19 (Fig. 3). Stop lever 39 is operated at the beginning and end of each code character and thus synchronism is maintained, as in the usual start-stop printer.

Shaft 26, driven by gear 25, is keyed to drum 43 (Fig. 3), which contains a plurality of operating bars 44, resting at their inner ends on fulcrum ring 45 on the drum (Figs. 3 and 9). These operating bars are notched where they engage the fulcrum 45 and are yieldingly held against the fulcrum by cap 46 and compression spring 47 surrounding shaft 26. The opposite ends of operating bars 44 have projections 48 fitting in slots 49 in the drum 43. The purpose of these will be

later explained. In the example given, there will be thirty-six of these bars, but only a few are illustrated to simplify the explanation.

Secured to a base 51 is a series of selector bars, ten in number, though, as later explained, the tenth bar may be omitted. It has been included in the illustration to better illustrate the principle of the selection. These are designated as a whole by the reference character 52. The base 51 is a part of, or is secured to, a cover plate 53a (Fig. 2) fastened to the printer base by suitable supports (not shown). The cover 53a is only fragmentarily shown in the figures, so as not to obscure the various co-acting parts that constitute my invention. The ten selector bars 52 are arcuate in form, as is usual in start-stop printers. These bars each have one cam arm 53 and are of identical dimensions and shape, except that the cam arms 53 increase in length successively from the bottom towards the top, as illustrated in Fig. 3. For example, the bottom or first selector bar (Fig. 5) has a short cam arm 53 that lies entirely in the plane of the first selector bar. The cam arms of successive bars increase successively in length by the thickness of a code bar. This is illustrated in Figs. 6 and 7, which show the length of the cam arms on the eighth and tenth selector bars, respectively. These cam arms, as shown in Fig. 3, thus have their cam ends aligned in the same horizontal plane just above the upper edge of drum 43. The operating bars 44, when in normal position, will not engage them, but will engage them when raised by mechanism later described.

35 The selector bars are held between pins 54 and 55 by a pair of vertical bars 57, each engaging the outer edges of the selector bars and fitting in slots 58 and 59 of the top plate 56 and base 51, respectively (Figs. 1 and 6). A flat spring 60 of 40 arcuate shape has its center fitting in a groove 61 in each bar 57 and its ends resting against a bushing 62 clamped between the top plate 56 and base 51 by bolt 63.

Each of the selector bars 52 has a slot 64 in its 45 mid-portion receiving the end 65 of an operating lever 66. There is an operating lever journaled on the bolt 67 fastened to the top plate 56 and base 51 (Fig. 1) for each selector bar. Each of these operating levers is urged clockwise in Fig. 50 1 by a spring 68, one end of which is fastened to bolt 63 and the other end to the end 65 of the operating lever. This stop lever moves between stop pins 67a and 67b. The top plate 56 is broken away in Fig. 1 to show this spring construction. 55 The operating levers 66 and 68 are of the same thickness as the selector bars, so that a selector bar and its operating lever can be freely moved independently of the other selector bars and operating levers.

60 The ends 69 of the operating levers 66 have a 50 connection of the ball and socket type with the ends of swords 70, ten in number in this case. Each sword has projections 71 and 72 adjacent the vertical prongs 73, 74 of a front armature extension 75 pivoted at 76. In Fig. 2 only one operating lever is illustrated, so as not to complicate the illustration. The armature extension is connected to armature 77 adapted to be attracted by line magnet 78 secured to the frame 70 23 by any means, for example, by bracket 79. The armature has a rear extension 81 with a hook 82 adapted, when moved by the line magnet on a mark signal, to engage trip latch 83 pivoted at 84 in the framing member 13 and move 75 it from engagement with stop lever 39. Spring

85 (Fig. 4) tends to hold this trip latch in engagement with the stop lever, with the end 42 in engagement with the abutment of clutch member 19 (Fig. 3).

When line magnet 78 is energized by a signal and the armature 77 is attracted, vertical prong 74 will be swung over abutments 12 of the swords 10. When the line magnet 78 is de-energized on a space signal, spring 86 turns the armature extension 15 in a clockwise direction, which brings the prong 73 opposite the projection 71 of the sword and disengages the end 82 from trip latch 83. The armature extension and sword arrangement is a well-known construction, shown, for example, in said Morton and Krum patent.

A spring blade 87 is secured to armature extension 15 by a suitable bracket 88. The free end of the blade carries a trigger insert 89 adapted to be placed between rod 90 and the cam lug 29 or 30 a brief time during each half revolution of cam wheel 28 (Figs. 11, 12 and 13). The rod 90 is slidably mounted in the frame members 21 and 22 (Figs. 1 and 2) and is adapted to engage and operate bell crank 91 when the trigger insert is placed between the rod and cam 29 or 30. The insert is placed in this position only on "space," that is, only when line magnet 78 is de-energized. On "mark" the trigger insert is removed by energization of the line magnet 78 and the cams 29 and 30 cannot then engage and operate the rod 90. The one or the other cam lug takes this position only during the mid-part of the first half of the dot cycle, as clearly shown in Fig. 16. The line magnet and its armature are removed from Fig. 2 to prevent obscuring of the other parts.

Bell crank 91, when moved by rod 90, engages an end of lever 92 and its other end then forces stop lever 39 down against the tension of its spring 41, so that its end 42 engages the abutment in the hub of slip clutch member 19 (Figs. 1, 3 and 4). This stops the rotation of shaft 20 and permits the spring 31 to move stop lever 31 out of the notch of the hub of clutch member 9. This starts the rotation of cams 5 and 6 and gear 8 simultaneously with the stopping of shaft 20. When the line magnet 78 is energized (mark) and latch 83 is released, rod 90 is forced back to its normal position by spring 41 acting through the stop lever 39 and bell crank 91. This disengages the end 42 from the clutch 19 and shaft 20 again rotates. When spring 41 performs this action, it also stops the rotation of cams 5 and 6 by forcing the stop lever 31 into engagement with cam wall 35 and abutment 36 of the clutch member 9 through bell crank 38. Thus, when shaft 20 stops, cams 5 and 6 and gear 8 rotate, and vice versa.

Adjacent the outside rim of drum 43 is a letter bar 93 slidably supported on rods 94 and 95, held by the support 96 secured to the base. Spring 95a tends to hold this bar in the position shown in Fig. 9, with the collar 95b against the support 96. The support 96 also furnishes a journal bearing for shaft 28 (Figs. 1, 3, 4 and 8). The letter bar 93 is angle-shaped in cross section and has the platform 97 and support 98. The support 98 is the portion that slides on rods 94 and 95. The mounting of the letter bar is such that the projections 48 on operating bars 44 pass freely under the platform 97 when in lowered position.

A tilting table or ramp 99 is pivoted at 100 in a block 101 fastened to the cover 53a (Figs. 8, 9 and 10). Spring 102 tends to pull the tilting platform against stop pin 103 and when in this position the projection 48 on the adjacent operating bar 44 engages the ramp, rides up its surface and

passes along the top of platform 97, in which position the operating bar engages the cam extensions 53 in succession as long as it remains on the platform.

As soon as the operating bar 44 rides over the dead center of the tilting ramp 99, it snaps the ramp to a horizontal position against stop pin 104. When this occurs, latch 105, pivoted at 106 in the arcuate support 98, snaps over the ramp and holds it in the elevated position. This movement is produced by spring 107 bringing the latch into engagement with stop pin 108. Thus, one operating bar 44 at a time is permitted to ride up the ramp onto the arcuate table 91. The next succeeding operating bar and all others pass under the ramp and platform 97, in the path between dotted lines 108a.

The construction is such that the upper edge of the end of the operating bar 44, when elevated, engages the cam projections 53 successively in the last halves, only, of the dot cycles and since the Morse telegraph code for letters and figures contains units varying in length from one dot cycle to ten dot cycles, means are provided to lower the elevated operating bar 44 as soon as the requisite number of dot cycles in the character have occurred. This is accomplished by pushing the platform 97 outwards at the end of the code signal and disengaging lug 48 therefrom. The operating bar then drops back to its lower position. This movement is produced by rod 110 (Figs. 1, 3, 4 and 8), cam 6, pin 111 and bell crank 112, as soon as clutch member 9 engages clutch member 3. The bell crank 112 is pivoted between ears 113 on the U-shaped support 96 and the pin 111 is slidably supported in the vertical bearing member of frame 18 (Fig. 3). The tension of spring 95a tends to keep sliding pin 111 in engagement with the surface of cam 6 through the intermediate parts just described, but this spring will yield when the cam rotates and forces the platform 97 outwards through such intermediate parts.

The swords 70, previously referred to, normally rest at the center of T-levers 114, of which there are ten. These T-levers are pivoted on pin 115 secured to the cover 53a (Figs. 1 and 15). The T-levers 114 operate code bars 116, of which there are ten. These bars are notched to receive the projection 117 of pull bars 118 when they have been operated to the correct position for the incoming signal (Figs. 1 and 2). There is, of course, a pull bar for each code character and also several others to perform certain functions in the printing, as is well known. In my improvement it is preferable to maintain the code bars in a position midway between the space and mark positions and this is accomplished by a slide 119 mounted in a channel guide 120 secured to the cover plate 53a (Figs. 1, 2 and 15). An angle iron 121 is mounted on the guide 120. Lever 122, pivoted at 123 to the angle iron, has a ball and socket connection with the slide 119. Guide 120 has a slot 124 to permit movement of this lever. Cam 5 operates rod 125, slidably mounted in frame 13 and 23. This rod engages lever 122 and holds pins 126, 127 against T-lever 114 with sword 70 at the center, as shown in full lines in Fig. 1. Spring 127a moves the slide and pins away from the T-lever and permits the sword to pivot and operate a code bar when the cam 5 permits.

The printing of the character, after it has been selected, is accomplished by gear 8, which meshes with idler 128 journaled in frame 13. This idler 78 meshes with gear 129 pivoted in frame 13, which

carries a printing cam 130. A cam follower 131, preferably in the form of a wheel, is journaled in lever 132 having a projection 133 engaging lever 134. Levers 132 and 134 are independently journaled at 135 in the frame 13 and their angular separation can be adjusted by stud 136. By suitably condensing the printing mechanism, the idler may be dispensed with and the cam 130 placed directly on the cam assembly containing cams 5 and 6. Lever 132, when moved by the cam 130, moves lever 134 counter-clockwise. When the cam surface recedes, spring 136a moves lever 132 through the stud 136 and maintains follower 131 in engagement with the cam. Lever 134 has a circular end 137 fitting in a slot in a bail-operating plunger 138. This plunger moves in bearings 139, 140, integrally joined together and secured to the base in a similar manner to that disclosed in said Morton and Krum patent. Plunger 138 carries at its upper end a bail 141 of arcuate shape similar to that of the code bars, as indicated in Fig. 1. The bail has a lip 142 adapted to engage the hook 143 of the selected pull bar 118 when it is moved upward, as such pull bar falls into the aligned slot in the code bars 116. The main printing cam, the operating levers, the plunger, the detail construction of the operating bail, the pull bars and code bars, T-levers and swords are, per se, not my invention and may be of standard form, for example, as shown in said Morton and Krum patent. For this reason, a detail showing of these parts is not made herein.

The operation of my improved telegraph printer will now be described:

As previously indicated, the design of the various gears is such that the cam wheel 28 (Figs. 1 and 13) makes one complete revolution for each two dot cycles. That is, one of the cams 29 or 30 passes the sliding rod 90 about the middle of the first half of each dot cycle. The diagram in Fig. 16 shows the relation of the parts in respect to a dot cycle. The elevated operating bar 44, however, moves past a cam projection 53 the last half of every dot cycle until lowered. Let it now be assumed that a signal for the letter A (dot, dash) comes in over the line and energizes magnet 78 accordingly (Fig. 1). Armature 71 will thus be attracted in the first half of the first dot cycle and rear extension 81 will bring the hook 82 into engagement with the trip latch 83 (Figs. 2 and 4). The trip latch is thus moved out of engagement with the stop lever 39 and spring 41 pulls the end 42 out of the notch in clutch 19. Since shaft 16 is constantly rotating, shaft 20 immediately starts revolving and rotates drum 43, operating bars 44 and cam wheel 28. Also, prong 74 on the front armature extension 75 is brought opposite the projections 72 of the sword 70 and prong 73 moves away from projection 71. At this time ramp 99 is in released position from its catch 105 and a lever 44 rides thereup and levels the ramp, after which latch 105 prevents the return of the ramp. In the last half of the first dot cycle (in Fig. 18 the last half cycles are numbered 1 to 10), the upper part of the end of the elevated operating bar 44 engages the cam projection 53 of the bottom or first selector bar 52 (Figs. 1, 5 and 17). The first selector bar is then moved a short distance clockwise in Fig. 1 until the end 65 of its operating bar 66 engages stop pin 67a. During this movement, the end 69 of the operating bar pulls the end of the sword to the right in Fig. 1 and its end 71 engages the prong 73, since line magnet 78 is de-energized in

the second half cycle (space) for the letter A (Fig. 18). This pushes the point of the sword 70 down to the position 144, shown in dotted lines in Fig. 1. The operating bar 44 then slides along the cam surface of cam 53 of the first selector bar and disengages therefrom. Operating member 66, however, cannot return to neutral position at this time, since the T-levers are held from moving by pins 126 and 127. These can be moved only by rotation of cam 5 when printing starts, as later described. The bar 57, spring 60 and the depth of the slot receiving end 64 permit movement of the letter bar 97 by passage of the member 44 over cam 53 at the end of the movement (Fig. 6).

The first half of the second dot cycle does not alter the operation, as clutch 19 has not been moved to stop position. During the second half of the second dot cycle (Fig. 17), the energization of magnet 78 by the mark signal positions prong 74 opposite projection 72. Soon thereafter the operating lever 44 (still elevated) engages the second cam 53 and causes its operating bar 66 to move the second sword to the right in Fig. 1. Projection 72 engages prong 74 during this movement and the end of the second sword is moved up to position 144a. Since clutch member 19 is still engaged with clutch member 17, nothing happens during the first half of the third dot cycle. The last half of the third dot cycle is a space, as shown in the code diagram of Fig. 18 and, as in the first dot cycle, the third sword will be moved to position 144 in engagement with the lower arm of its T-lever.

The code signal for the letter being completed, the first half of the fourth dot cycle is a letter space and at the middle of this half cycle either the cam 29 or 30 on cam wheel 28 is opposite the rod 90. Since magnet 78 is not energized for a space, trigger insert 89 is positioned between the cam projection and rod 90. Therefore, upon a slight further movement of the wheel 28, rod 90 is pushed to the left in Fig. 4 and stop lever 39 is forced downwards into engagement with the notch in clutch member 19 through the movement of bell crank 91 and lever 92 (Figs. 3 and 4). Shaft 20 thereupon stops, the friction surface between clutch members 17 and 19 permitting this. Simultaneously with this action, the movement of the outer end of lever 39 permits spring 31 (Fig. 2) to move bell crank lever 38 and disengage stop lever 31 from the channel 33 in clutch member 9. Spring 10 thereupon brings clutch member 9 into engagement with clutch member 3, and cams 5, 6 and gear 8 start to rotate, substantially simultaneously with the stopping of shaft 20. Depression 145 on the surface of cam 5 immediately passes under rod 125 (Figs. 1 and 14) and spring 127a moves slide 119 with pins 126 and 127 to the left in Figs. 1 and 2. The tension in springs 68 of the three previously moved operating levers 66 thereupon pushes the ends of the first, second and third swords 70 to the left against their T-levers 114, which rotate the first and third T-levers clockwise and the second one counter-clockwise. This moves the first and third selector bars up in this figure or to the left in Fig. 17, as indicated by the arrow S. The second selector bar is moved down in Fig. 1 or to the right in Fig. 17, as indicated by the arrow M. This produces a line of slots under the projection 117 of pull bar 118 for the letter A, since code bars 4 to 10, inclusive, are slotted in the center position as shown in Fig. 17. At about this time, elevation 146 on the surface of

cam 6 engages rod 110 and pushes letter bar 93 outward (Figs. 4 and 8), against the tension of spring 95a, by means of pin 111, bell crank lever 112 and rod 110. Projection 48 of the elevated bar 44 then disengages the table 97 of this letter bar and the operating bar drops down to its lowered position after having engaged the first, second and third cam projections 53. As the table moves outward, latch 105 slides off the ramp 99 and it returns to the tilted position, under action of spring 102 (Figs. 8, 9 and 10), where it remains until the start of the next code unit.

At about the time the operating bar is dropped, main printing cam 130 moves levers 132 and 134 and elevates operating plunger 138 (Fig. 2). As this plunger moves upwards, the extension 117 of pull bar 118 drops into the aligned slots in the code bars 116 and edge 142 of the operating bail 141 engages the hook of this pull bar. Upon its further movement, it engages the striker plate 148 and the pull bar is disengaged from the bail 141. The momentum of the pull bar continues the motion of the key bar (not shown) and prints the letter A in a way well known in the prior art, explained, for example, in said Morton and Krum patent. This printing operation occurs during a letter space, which is one dot cycle.

After the pull bar 118 is thrown out of the slot in the code bars by the striker plate 148, rod 125 leaves the depression 145 (Fig. 14) and this forces the slide 119 back so that pins 126 and 127 move the T-bars 114 to center position. This moves the code bars 116 back to neutral position before the next dot cycle commences.

In the first half cycles of all characters, the swords are not moved, because a cam 53 is never engaged by the operating member 44 in the first half cycles. Engagement occurs only in the second half of the cycles, providing an operating member is on the platform 97.

Now let it be supposed that the letter N is received. This letter consists of a dash and a dot. When the first dot cycle of the signal is received (mark), the line magnet 78 is energized and its rear extension 81 trips the latch 133. Stop lever 39 moves out of the notch of clutch 19, which immediately permits shaft 20 to rotate. Simultaneously, bell crank lever 38 is moved and stop lever 31 is forced into the groove 33 of clutch member 9. This happens at about the time the stop lever is adjacent the cam wall 35 on the clutch and a slight further movement disengages clutch member 9 from clutch member 3. The hook end of stop lever 31 then rests against the abutment 36 and holds the cams 5 and 6 and gear 8 in a definite position ready for the next printing operation.

During the last half of the first cycle of the mark of letter N that has just started, the adjacent operating member 44 rides up the tilting ramp 99. This operating lever will thus be elevated onto the platform 97, as previously described, whereupon the ramp 99 will latch into position again. This elevated operating bar will engage the first cam projection 53 and move the first sword 70 to position 144a, as previously described for the letter A. Line magnet 78 will not be energized in the second half of the second cycle, as shown by Fig. 18, and when the elevated bar 44 engages the second cam projection 53, the second sword 70 will be moved down to position 144 in Fig. 1. The last half of the third cycle of the letter N is a space and magnet 78 will be de-energized when the third cam 53 is engaged by member 44. The third sword 70

will therefore be moved down to position 144. The first half of the fourth dot cycle is a letter space. Line magnet 78 remains de-energized and trigger insert 89 is positioned between rod 90 and cam 29 or 30. Therefore, stop lever 39 will have its end 42 forced into the notch of clutch member 19 and shaft 20 will stop. This permits bell crank lever 38 to move and lever 31 leaves the abutment 36 on clutch member 9. Cams 5 and 6 and gear 8 immediately start to rotate and release pins 126, 127, which move away from the T-levers. Springs 68 then move the first T-lever counter-clockwise and the second and third T-levers clockwise. This moves the first code bar to the right in Fig. 17 and the second and third code bars to the left. Slots in these three code bars and those in the seven other bars in neutral position will be positioned under the pull bar for the letter N, which will move thereinto and the letter N is then printed in the way described for the letter A.

In a way that will now be understood, all of the characters are printed directly by the Morse code signal pulses without any perforated tape. This occurs as the signals are received, so there is no time delay as in prior art Morse code printers.

An examination of Fig. 17 will show that slots are cut in all code bars that need to be moved for a given character, so that slots are positioned to the left of the pull bar for a mark in the last half cycles and to the right for a space in the last half cycles. All the unmoved code bars for such character will be in center position due to the retracting action of pins 126 and 127 under pressure of rod 125 and cam 5. These unmoved bars have slots under the pull bar of the character. For example, for the character G, code bars 1 to 5, inclusive, will in neutral position have unslotted portions under the pull bar for that letter, and code bars 6 to 10, inclusive, will have slots thereunder in such position. The first and third bars will have slots at the left, and the second, fourth and fifth bars will have slots to the right. The character zero will have no slots under the pull bar for that character, as it has five dashes and all ten code bars are moved in the selecting process. The way in which the slots occur for the other characters will be apparent from an inspection of Figs. 17 and 18 and this need not be further described. While it gives a margin of safety in operation to have as many selector bars, code bars and associated members as there are last half cycles (ten in Fig. 18) of the code used, the bars and members for the final half cycle (tenth in Fig. 17) may be omitted without duplicating any other selection.

By way of example I have shown a particular mechanism to disclose my invention, but it will be apparent that many modified forms of signal storage would produce similar results. The invention is therefore not to be limited to any particular embodiment.

It will be understood that the usual spacing arrangement will be used to move the tape or other sheet as the characters are printed. This and other features are well known in the art and have not been illustrated or described.

Having described my invention, what I claim is:

1. In printers for codes having characters of unequal length, a plurality of code members, said code members having a mark position, a space position and a neutral position intermediate thereof, a plurality of printing members, means for selecting predetermined ones of said code

members for movement to mark and space positions during the last half of each dot cycle of the received signals of a code character, means for starting the operation of the first-mentioned means during the first half of the first dot cycle of the received signals of a code character, means for positioning the unselected code members in neutral position, said selected code members after said movement and said unselected code members in neutral position having slots to receive a member for printing the code character of the received signals, and means for stopping the operation of said first-mentioned means and starting the movement of said printing member into said slots in the first half cycle of the space immediately following the last dot cycle of the received signals of the character.

2. In printers for codes having characters of unequal length, a plurality of slotted code bars, said code bars having a mark position, a space position and a neutral position, a selector shaft, means for starting the rotation of the selector shaft during the first half of the first dot cycle of the received signal, means operated by said shaft in the last half of each dot cycle of the received signal for selecting predetermined ones of said code bars for mark or space position, printing means for the code characters, said selected and unselected code bars having slots aligned with one of said printing means for the code character of the received signal, means for stopping the rotation of said selector shaft in the first half cycle of the space immediately following the last dot cycle of the received signal, and means for returning the selected code bars to neutral position.

3. In printers for codes having characters of unequal length, a plurality of code bars, said code bars having a mark position, a space position and a neutral position, a selector shaft, means for starting the rotation of the selector shaft during the first half of the first dot cycle of the received signals of a code character, means operated by said shaft in the last half of each dot cycle of the received signals of a code character for selecting predetermined ones of said code bars for movement to mark and space positions, means for stopping the rotation of said selector shaft in the first half cycle of the space immediately following the last dot cycle of said received signals, and means for simultaneously moving the selected code bars to mark and space position.

4. In printers for code characters of unequal length, a rotatable shaft, a drum rotatable by said shaft, a plurality of radial bars in said drum, a plurality of code bars, a plurality of T's for engaging said code bars, a plurality of swords for engaging said T's, cam members for positioning said swords against said T's, means for starting said shaft into operation upon occurrence of a mark in the first dot cycle of a signal, means for

moving one of said radial bars into engagement with said cam members in the subsequent last halves of the dot cycles, and means for stopping the rotation of said shaft and for disengaging said radial bar from said cams upon the receipt of the first half of the dot cycle of a space.

5. In printers for code characters of unequal length, a rotatable disc, a plurality of radial operating bars pivoted on said disc, means for starting the rotation of said disc during the first half of the first dot cycle of the received signals of a code character, a plurality of selector bars positioned above and out of line with said operating bars, means for raising one of said operating bars into line for successively engaging said selector bars, and means for depressing the last-mentioned operating bar after the first half of the first dot cycle succeeding said signal.

6. In printers for code characters of unequal length, a rotatable disc, a plurality of radial operating bars pivoted on said disc, means for starting the rotation of said disc during the first half of the first dot cycle of the received signals of a code character, a plurality of selector bars positioned above and out of line with said operating bars, a plurality of code bars adapted to move in either of two directions, means for raising one of said operating bars into line for successively engaging said selector bars, means for moving the code bars by said selector bars upon movement of the operating bars, means to determine the direction of motion of the code bars by the character of the signal in the first half of the first dot cycle of a signal mark, and means for depressing the last-mentioned operating bar after the first half of the first dot cycle succeeding said signal.

7. In printers for code characters of unequal length, a rotatable drum having a plurality of radial operating bars, means for rotating the drum at the start of the code signal, a plurality of code selector bars having projections above said operating bars, a pivoted inclined ramp for elevating an operating bar into line with said projections, said operating bar moving the ramp out of inclined position, means for latching said ramp after movement by the operating bar, and means for unlatching the ramp when the code signal ends.

50 RICHARD E. MATHEIS.
